UNITED STATES PATENT OFFICE

ALBERT PERLING, OF PARIS, KENTUCKY

AUTOMATIC MERCHANDISE DISPLAYING DEVICE

Application filed May 29, 1930. Serial No. 457,102.

This invention relates to display devices, and is more particularly concerned with a display device mounting and periodically moving in succession a series of dresses, etc. and 5 constructed automatically to display in succession the fronts and backs of a series of dresses or other articles with successive pauses between movements of the dresses permitting inspection of their fronts and backs.

10 A device of this character is shown in my prior Patent No. 1,717,246, granted June 11, 1929 and the present invention constitutes an improvement thereon in respect to the dress supporting and displaying mechanism and in 15 that provision is made for successively displaying for view from one position of observation the front and back of one dress, and for the display of two different dresses at the same time, with the front displaying dress, 20 for example, subsequently moved and positioned to display its back view and the front of a succeeding dress coincidently displayed for view, thus providing means for displaying successively the front and back view of each 25 of a series of entirely different dresses, suits or cloaks, for example.

One feature of the invention consists in the provision of a trackway supported from a base and having a curved portion, with a row 30 of movable display units mounted upon a portion of the trackway and provision of means for intermittently moving successive display units around a curved portion of the trackway, with intervening inspection periods be- 35 tween movements of successive units. With such a mechanism, different views, such as front and back views of a unit carried display will be successively presented to view from an observation point at one end of the track with 40 the interval between successive movements of the units providing time for inspection of different views.

Another object of the invention is the pro- 45 vision with a trackway having curved end and connecting side portions and a row of movable display units mounted on each side portion between its opposite curved ends, of power driven means for intermittently moving successive end display units from opposite 50 ends of opposite side portions of the trackway

around the opposite curved ends thereof in the same rotative direction to the opposite sides of said curved ends and step by step with the row of units at that side longitudinally of the side portions in the same rotative direction, with intervening inspection periods between movements of successive units. With such a mechanism, successive ones of the rows of display units at opposite sides of the trackway are individually moved around the curved ends of the trackway at successive intervals, so that a complete circulation of the display units is secured with each display unit passing around the opposite curved ends of the trackway and with the display observable from either end. Other features and advantages will be apparent as the invention is later developed in descriptive detail.

Such a device may be used to advantage in the show windows or display rooms of stores and shops and has the advantage, in addition to its display function, of attracting attention and securing inspection of displays.

The invention consists in the construction, arrangement and combination of parts as hereinafter described and claimed and will be more clearly apparent from the following detailed specification which is to be read in conjunction with the accompanying drawings forming part thereof, and in which:—

Figure 1 is a front end elevation of a display device constructed in accordance with the present invention.

Figure 2 is a top plan view thereof.

Figure 3 is a longitudinal vertical section on the line 3—3 of Figure 2.

Figure 4 is a detail in side elevation on an enlarged scale of two adjacent hanger units on the side of the trackway with the actuator arm riding down the camming incline of a cam way to engage the rear abutment face of an outer hanger unit to initiate movement thereof.

Figure 5 is a top plan view of a modified form of the invention employing dual actuating arms.

Figure 6 is a longitudinal vertical section on the line 6—6 of Figure 5.

Referring particularly to Figures 1, 2 and 3, it will be seen that a trackway 1, which may

be circular in cross section, is provided with opposite curved ends 2 and 3 connected by side portions 4 and 5 shown as straight and parallel but which may be curved or otherwise as desired. This trackway is supported by a plurality of relatively thin flat spokes 6 radiating outwardly from a hub 7 centrally apertured and fitting over and secured to the upper end of a tubular supporting standard 8 whose lower end extends through a vertical bore 9 formed in the upper end of a hollow base 10 and is fixed therein by a series of bolts 11 inserted through a boss 12 edging the bore 9 and into the lower end of the tubular standard 8.

Preferably, and as shown in Figure 3, the hollow base is formed of a cupped metal casting having flanges 13 extending inwardly from its lower edges which are designed to rest upon the floor or other stable support. A plate 14 is supported on these flanges and fixed thereto and mounts on its upper face a small electric driving motor 15 having a pulley 16 mounted on the extended end of its shaft. Beneath and in axial alinement with the tubular standard 8 is a gear casing 17 of suitable construction in which is journaled and from which extends vertically upward a driving shaft 18 rotated through belt drive and intervening reducing gearing from the driving pulley 16 of the motor. This reducing gearing may take any suitable form, such for example, as a worm gear on shaft 18 meshing with a worm on the transverse shaft 19 which projects outwardly from the casing and carries a pulley or other driving element 20 thereon connected by a belt or other wrapping connector 21 with the pulley 16 of the driving motor. A tubular sleeve 22 of lesser external diameter than the internal diameter of the standard 8 encases and is secured to the shaft 18 and extends upwardly with said shaft through the bore in the hub 7 to a point above the plane of the trackway 1, the sleeve 22 terminating below the upper end of the shaft 18 and supporting the under face of the inner end of a yoke arm 23 clamped thereto and rotating therewith and with the shaft 18 by means of the nut 24 threaded over the upper threaded end of shaft 18 as shown in Figure 3. This yoke forms part of a rotating actuating arm for certain display units mounted on the trackway as hereinafter described and extends radially outward from the hub 7 and shaft 18 and has its outer end bifurcated as at 25, Figure 2. The inner end of an actuating arm 26 is pivotally mounted between bifurcation 25 on a horizontal pivot stud 27 for upward and downward movement in a vertical plane. The outer end of the actuating arm, which is of rectangular cross section, has its lower face bevelled upwardly to substantially triangular cross section, as shown in Figure 4, and its outer end curved inwardly and rearwardly, as shown in Fig.

2, for cooperating with the abutment faces of a series of individually movable display units mounted on the trackway.

As shown in Figure 2, a series or row of individually movable display units 28 are mounted in abutting relation on the opposite side portions 4 and 5 of the trackway between the opposite curved ends 2 and 3 thereof. These display units 28 are in effect rolling hangers to receive articles to be displayed, such as dresses, coats, suits, etc. and, as shown, are hollow vertically elongated casings substantially rectangular in vertical and horizontal cross section, providing a hollow rectangular internal area 29. The inner side faces of this casing are completely traversed by a horizontal slot 30 of a width somewhat greater than the diameter of the circular cross section of the trackway 1 to permit the insertion of the units thereon. Within the hollow interior 29 of these casings above and below the horizontal slot 30 are mounted a pair of tracks embracing concaved rollers 31 revolubly mounted on spindles 32 extending through the opposite side walls of the casings and engaged and retained in position by nuts 33 threading on their outer ends. Suitably attached to the bottom face of each casing is a clip 34 having a depending hook 35 designed to receive the supporting hook 36 of a garment hanger 37 as shown in Figures 1 and 3. The upper ends of the rear faces 38 of these hanger unit casings constitute abutment or thrust receiving faces for the forward end face of the actuating arm 26 and the forward top faces of the casings are provided with a downwardly inclined bevel 39, best seen in Figure 4, to permit the lower beveled face 26a of the end of the actuating arm 26 to slide downwardly over this incline on the top of the next to end unit of a row to bring the forward face of said arm against the rear abutment face 38 of the end unit as will be clear from Figure 4 and as later described in the operation. These downwardly inclined bevels are diagonal to the top face of the unit casings on lines which, as will be seen from Figure 2, are substantially radial to the shaft 18 representing the axis of rotation of the arm 26 so that the rotative path of movement of the arm with its downward component of movement permitted by its pivotal mounting 25 will move it naturally towards the incline 39. It will be evident that when the shaft 18 and its sleeve 22 are rotated at reduced speed through the drive motor, the actuating arm formed by the yoke 23 and its pivoted arm extension 26 will swing about a vertical axis and in an arc including the opposite curved ends 2 and 3 of the trackway. Means is provided for guiding this arm to effect movement of an end display unit 28 at one side portion of the trackway around the adjacent curved end thereof to the opposite side of

the trackway to impact the units at that side of the trackway and move them one step forwardly in the rotative direction of the arm, thereafter to lift said arm from operative engagement with a display unit as it continues to rotate; and to bring it into operative thrusting engagement with the abutment end of the unit at the opposite end of the trackway at that same side moving that unit 10 around the opposite curved end of the trackway to the opposite or first side portion to impact the row of units at that first side and move them forwardly one step in the direction of rotation of the arm; the arm thereafter being lifted from contact with the unit and guided forwardly to engage the outermost unit and start the cycle over again. This mechanism functions in a sense as a pawl and ratchet, the arm 26 constituting the pawl. 20 To thus control the unit operating movements of the arm 26, the following means is provided. Supported from and spanning pairs of radial track supporting arms 6 at each side of the longitudinal median line of 25 the trackway (which includes the axis 18 of rotation of the arm 26) are arm controlling cams 40. As best seen in Figures 2 and 3, these cams are in the form of bars elevated above and spanning pairs of radial arms 6 and formed with opposite upwardly inclined elevating and depressing end bar portions 41 and 42, respectively, uprising diagonally from the respective pairs of radial arms 6 and connected by an intermediate horizontal 30 "dwell" or elevation maintaining portion 43, the respective bar elevating and depressing end portions of these cams being reversed at opposite sides of the longitudinal median line of the trackway as shown in Figure 2 to have the elevating and depressing or lowering portions function in succession in the continued rotation of the arm 26, through a complete revolution about its axis.

With the described construction in mind, 45 the operation of the form of the device shown in Figures 1 and 4, inclusive, will be as follows: Assume that at the start of the operation, the outer end of the arm 26, is positioned, as shown in dotted lines at A, Figure 2, 50 at the end of the side portion of the trackway adjacent to its curved end 3, to which position it is lowered through the cam portion to rest the forward face of its actuating end against the abutment face 38 of the endmost unit 28, as shown in Figure 4, which endmost unit in Figure 2 is shown in dotted lines; rotation of the arm 26 through shaft 18 commences in a counterclockwise direction. 55 As the arm moves in this direction, it continues to lower until its lower face rests on the trackway 1 immediately in rear of the unit 28 and moves said unit on its roller over the trackway 1 toward the opposite side portion 4 of the trackway. The midway position of the arm 26 and the display unit 60 which it is thus actuating is shown in full lines at the side of Figure 2. The arm continues to rotate counterclockwise from this full line position toward the opposite side portion 4 of the trackway until the moving unit 28 abuts the adjacent end unit 28 of the row on that side portion 4 at which point the under face of the arm 26 contacts with the elevating incline 41 of the cam 40 at that side of the trackway and begins to lift the 65 arm 26 as the arm continues to rotate, the lifting movement being figured to terminate when the actuated display unit 28 has abutted and moved the row of units 28 at trackway side 4 to the extent of the length of one unit, 70 moving the unit 28 at the opposite end of the row to the dotted line position shown in Fig. 2 at the upper left hand end. At this point, the arm 26 clears the display units 75 and continues to move over the elevated horizontal dwell portion 43 of the cam, clearing all intermediate units. The lowering portion 42 of the cam, however, is so positioned as to lower the outer end of the arm 26 as it passes over the bevel 39 on the top face of the 80 now next to end unit, lowering the end of the arm to contact with the abutment face 38 of the now end unit (shown in dotted lines, Figure 2) in the manner suggested in Figure 85 4 so that continued rotation of the arm will move said end unit around the opposite curved end 2 of the trackway to abutting relation with the adjacent end unit 28 at the side portion 5 and advance that row to the extent of the length of one unit at which 90 point the elevating portion 41 of the cam 40 of that side of the trackway has functioned to lift the arm 26 to clear the row of units with its dwell portion 43 acting and maintaining the arm out of contact until it approaches the opposite end unit position corresponding to the first unit acted upon when the lowering incline 42 of the cam brings it 95 into contact with that unit. This will complete a cycle or revolution of the actuating arm from which it will be seen that the arm 26 functions to move a series of single display units from opposite ends of opposite side portions of the trackway in the same rotative direction around the opposite curved end portions thereof where it acts to give step by step movement to the row of units at that side longitudinally of the side portions. The dwell portions 43 of the cam provide intervening inspection periods of time 100 between movements of successive units and each individual unit of the whole series is thus intermittently moved around a curved end of the trackway. With a series of dresses, coats or suits mounted on the hangers 105 37 and suspended from the display units, it will be seen that a spectator standing to view one curved end portion of the trackway will, as suggested in Figure 1, view the front of a dress at the left side before the display unit 110 115 120 125 130

is moved and at the completion of the movement of the display unit to the opposite side of the trackway around its curved end will view the back of the same dress at the right side with the front of another dress displayed at the left side and so on. Thus the appearance of the front and back of each garment or other exhibit carried by the display units are successively disclosed during successive 10 inspection periods and by reason of the intermittent movement of the display units at each curved end of the trackway, the same dresses may be seen, thus displayed, by persons standing at the opposite ends of the trackway 15 so that it is possible for the exhibit audience to be doubled in number with the two opposite ends of observation.

In the form of the invention described and shown in Figures 1-4, the display unit capacity 20 of the trackway is limited by reason of the necessity of limiting the spacing of the opposite curved ends of the trackway and therefore the unit capacity of the side portions to the diameter of the circle of rotation 25 of the arm 26, it being understood that the length of the arm 26 as shown in full lines in Figure 2 coincides substantially with the radius of the circle represented by the curved ends 2 and 3 of the trackway. Obviously, these ends may be on a curve somewhat 30 greater than the curvature of the circle, or less, with the length of the arm 26 varied correspondingly and of an over-all dimension to extend over the trackway at the most distant point of the latter from its axis of rotation.

In Figures 5 and 6, I have shown a modified arrangement embodying the same operative principles but adapting the device, in 40 principle, to carry a greater number of exhibit or display units. In this form of the device, the trackway will have greater longitudinal dimension to provide a greater unit storage length for its side portions 44 and 45. Its curved end portions 46 and 47 will preferably be formed on the curvature of a circle and the trackway will be supported by flat horizontally extending arms 48 radiating from a hub 49 corresponding to the hub 50 7 of the first form of the device and similarly supported upon the upper end of a tubular supporting standard 50 corresponding to the standard 8, the base and operating connections being similar to those shown in the first 55 form of Figures 1-4. A sleeve 51 corresponding to the sleeve 22 extends upwardly through the central bore of the hub 49 and encloses a drive shaft 52 corresponding to the drive shaft 8 of the first form of the device. Seated over the upper end of the sleeve 51 and clamped thereon and to the drive shaft to rotate therewith by the nut 53 is a central actuating gear 54. This central driving gear 54 which is positioned in a 60 horizontal plane with its axis in the longi-

tudinal median line of the trackway meshes at diametrically opposite points in said median line with arm driving gears 55 and 56 having hub sleeves 57 projecting from opposite upper and lower faces thereof and extending at their lower faces downwardly through bearing bosses 58 upstanding from the top faces of transverse bars 59 cross connecting divergent radial arms 48 at the opposite curved ends of the trackway with the axis of the hubs representing, preferably, the center of the circle on which the curvature of the ends 46 and 47 are generated. The lower faces of the gears 55-56 rest on and have suitable bearing contact with the bosses 58. The upper ends of the hub sleeves 57 support the under faces of yoke arms 60 having bifurcated outer ends mounting the inner ends of actuating arm 61 and corresponding to the yokes and actuating arms of the first form of the invention, therefore requiring no further detailed description. Preferably, a short vertical shaft 62 extends through and is fixed with the hub sleeve 57 to rotate therewith the upper and lower ends of the shafts projecting beyond the yoke 60 and the lower end of the hub sleeve 57 being engaged by nut 63 threaded thereon and rigidly clamping the yokes 60 to the gear hub sleeves 57 to rotate therewith.

The gears 54, 55, 56 extend in the same horizontal plane, with the yokes 60 elevated substantially thereabove and the arm 61 normally by gravity tending to drop down to rest upon the edge of the trackway at their outer ends. In accordance with the cams 40 of Figures 1-4, cam arms 64 extend oppositely inward from the transverse supporting bars 59 toward the hub of the central actuating gear 54. These cam arms are curved upon the axis 62 of rotation of the gears 55-56 and are substantially semi-circular in top plan view as shown in Figure 5. They are concentric with and outwardly of the edges of the gears 55 and 56 and are provided, as shown in Figure 6, with opposite arm elevating and depressing end portions 65 and 66 respectively and an intermediate horizontal dwell portion 67. The display units 68 which are arranged in rows at the opposite side portions 44 and 45 of the trackway correspond in structure to the display units 28 of the first form of the invention and need not be further described. Their co-operation with the actuating arm is similar with the only difference in operation consisting in the fact that the opposite end arms 61 function only to move the end display units at their end of the trackway, the dwell portion 67 of their cams being effective for approximately $\frac{1}{2}$ of the revolution of the arms to maintain them in a plane out of engagement with any of the display units during their sweep inwardly over the inner half of their circle of movement.

Preferably, in order to provide adequate inspection intervals between the successive movements of the displaying units by the two arms 61, their gears 55 and 56 are meshed 5 with the central driving gear 54 to cause the arms to extend in substantially 45° angular relation. Obviously, the central driving gear will transmit to the arms 60 and 61 revolving movement about their axes in the same 10 direction of rotation so that the units will be successively transferred around the curved ends of the trackway from one side portion as 44 to the opposite side portion, as 45, and from that opposite side portion 45 back again 15 to the first side portion 44, the movements of the respective arms 61 being figured to not only slide an individual unit around the curved end of the trackway but through that unit to impart step by step longitudinal 20 movement to the rows of units at the side of the trackway to which the unit is swung as in the first form of the device by utilizing two arms 61 with their axes of rotation in the longitudinal median line of the trackway 25 and sufficiently spaced to prevent interference. Substantially longer side portions 44 and 45 of a trackway may be provided and a substantially greater number of display units may be mounted thereon with the movement 30 of individual units maintained at the proper speed of exhibit by reason of the use of duplicate actuating arms. The same operative principle is effective in both forms of the device, each of which, as shown, while representing a preferable form of the invention, 35 is intended only as illustrative thereof and not as restrictive and is subject to structural modification and change to adapt the invention to different conditions of manufacture 40 and use in consonance with the spirit of the invention and the scope of the appended claims.

What I claim, therefore, and desire to obtain by Letters Patent is:—

1. A display rack comprising a base, a trackway supported from said base in a horizontal plane having a curved end portion and connected side portions, a row of individually movable display units mounted on 45 each side portion of the trackway and having spaced abutments thereon, an actuating arm mounted and operative revolvably to swing in a horizontal plane through an arc including the curved end of the trackway and 50 side portions adjacent thereto, said arm including an outer operating end supported for movement in a vertical path coincidently with swinging movement in a horizontal plane, and arranged to contact said display 55 unit abutments bodily to move individual units over said trackway, and a cam way cooperating with said outer arm portion and formed to cause said outer arm to move vertically to engage the abutment of an end unit 60 of the row of display units on one side por-

tion of the trackway and to swing with said unit around the curved end of said trackway to the opposite side portion thereof to contact said unit with the row of units on 70 said opposite side portion and impart determinate coincident bodily movement to said unit and the contacted row of units longitudinally of said side portion, thereafter to vertically move said outer arm from moving contact with said unit and to determinately maintain it in such inoperative position and then vertically to move it to engage and move the next end unit on the first named side portion of the trackway around the curved end thereof on the next revolution of 75 said arm.

2. A display rack comprising a base, a continuous trackway supported from said base in a horizontal plane having opposed curved end and connecting side portions, a row of individually movable display units mounted upon each side portion of the trackway in abutting contacting relation with said units having spaced abutments on their upper portions, an arm mounted and operative revolvably to swing in a horizontal plane vertically spaced from that of said trackway and units through an arc including a curved end portion of the trackway and side 80 portions adjacent thereto, said arm having an outer operating portion mounted for swinging movement in a vertical plane toward and from said trackway and units coincidently with its bodily horizontal swinging movement, and means for guiding said outer arm position for vertical movement during each revolution thereof to cause said outer portion to engage and move a single display unit from one end of a row at one 85 side portion of the trackway around the adjacent curved end portion thereof to the opposite side portion and for a determinate distance with the row of units at that opposite side portion, longitudinally of said side portion, and thereafter to move vertically to release the engaged unit and to swing through a determinate arc in a horizontal plane without contact with display units.

3. A display rack comprising a base, a continuous horizontal trackway, a support upstanding from said base, a plurality of supporting arms radiating from said support and rigidly connected to the inner sides of said trackway, cams mounted upon certain of said arms and projecting above said trackway, a series of display units movably mounted on said trackway, each of said display units having abutment surfaces, a rotatable means including a vertically movable arm, said arms adapted to engage said cams for movement thereof into and out of engagement with the abutments of said display units.

4. A display rack comprising a base, a continuous trackway supported from said 130

base in a horizontal plane having opposed curved ends and connecting side portions, a row of individually movable display units mounted upon each side portion of the trackway in abutting contacting relation and having spaced abutments on their upper portions, a rotatable arm mounted adjacent each curved end portion of the trackway, means for simultaneously rotating said arms, said arms including an outer operating end supported for movement in a vertical path coincidently with rotary movement thereof and arranged to contact said display unit abutments, and a respective cam member cooperating with the outer end of each of said arms and formed to cause said outer end to move vertically to engage the abutment of an end unit of the row of display units on one side portion of the trackway and to swing with said unit around the curved portions of the trackway to the opposite side thereof to contact said unit with the row of units on opposite side portions and impart bodily movement to the contacted row of units, thereafter to vertically move and maintain said outer operating ends from contact with said units and then vertically move said operating ends to engage and move the next end unit on the next revolution of said arms.

ALBERT PERLING.
